UNITED STATES PATENT OFFICE.

ROBERT T. ST. JAMES, OF CHICAGO, ILLINOIS, ASSIGNOR TO CHICAGO MINIATURE LAMP WORKS, OF CHICAGO, ILLINOIS, A CORPORATION OF ILLINOIS.

PROCESS FOR EXHAUSTING DETECTOR TUBES.

Application filed April 10, 1922. Serial No. 551,150.

This invention relates to an improved process for exhausting the vacuum tubes or receptacles of detectors for wireless telegraph and telephone systems, and consists **5** of the matters hereinafter described and more particularly pointed out in the appended claims.

The object of the invention is to provide a process for exhausting the vacuum tubes, **10** bulbs or receptacles of detectors, whereby the quality, efficiency and life of such detectors is greatly increased. Detectors exhausted by the improved process are uniform in character and operation and are substantially free of the extraneous noises and tone-**15** confusing vibrations generally attendant upon the use of detectors now on the market.

The advantages of the invention will appear as I proceed with my specification. **20** The improved process may be advantageously used in exhausting the receptacles of any of the well known detectors, but the best results are produced when the process is applied to detectors having a hot and cold **25** electrode and an interposed grid or intensifying element, and more particularly where said elements consist of a central filament; of a cylindrical plate element surrounding the filament; and of an intensifying coil **30** supported at one end only, located in the space between the inner surface of the cylindrical plate and the filament. Such a detector is described in an application for patent executed by me of even date herewith.

The process may be carried out as hereafter described by means of any suitable apparatus, and in the accompanying drawing, for the purpose of illustration, I have shown diagrammatically and conventionally **35** such an apparatus. In said drawing

40 10, 10, 10 indicates a plurality of detector tubes each tubulated and connected to a manifold 11. Said tubes are enclosed in a chamber 12 which is adapted to be heated, **45** by the coils 13. 14 indicates an exhaust pump connected to the manifold 11 and driven by a motor 15. 16 indicates a three way valve in the manifold 11, which is connected at the valve by a pipe 17, leading **50** from air dryers 18, 19 of familiar type. 20 indicates an air core high frequency transformer with the secondary coil connected on one side to the metal elements of the detector tubes and on the other side to ground. **55** 21 indicates an iron core step-up transform-

er; 22, a condenser; and 23 indicates a spark gap.

24 indicates the conductor which is adapted to connect the above mentioned secondary coil to the metal elements of the detector **60** tubes and 25 a switch interposed therein. 26 indicates a conductor and 27 another conductor which is connected to it in series with the filaments of the several tubes. By the two conductors and a switch member 28, the **65** said filaments may be connected as illustrated to a source of alternating current supply to heat them, when the switch 25 is open. 29 indicates a conductor connected to each of the grids of the several tubes. **70** 30 indicates a conductor to which the several plate elements are connected. Said conductor is connected to the positive side 31 of a source of direct current supply at 220 volts by a switch 31^a. A switch 32 is adapted to **75** bridge and connect the three conductors 30, 29 and 26. With the switches 32 and 25 closed (the other switches being open) the conductor 24, leading from the secondary coil of the high frequency transformer, will **80** be connected simultaneously to the three elements of the several detector tubes. With the switches 32 and 25 open, and the switches 31^a and 28 closed, the filaments will be heated and the plates of the several elements will have imposed upon them a voltage of 220 volts. **85**

The improved process is as follows: The metal parts, including in the case of a detector of the kind described, the hot and cold electrodes and the grid or intensifying coil mounted between them, after being mounted in the glass sealing stem or plug for the glass tube, bulb or other receptacle of the detector, are first thoroughly washed **90** and cleansed to remove all foreign or extraneous substances. This cleansing or washing step may be best done by immersion and agitation of the metal parts in high-proof gasoline (84 spec. grav.) or in **95** ether or the like cleansing agent.

The object of this step of the process is to eliminate and remove from the surfaces of the metal parts any and all particles of foreign substance, which in the subsequent and final exhausting of the receptacle, or later during its use, would form gases. **105**

Immediately after the cleaning of the metal parts, the glass plug carrying them is sealed in the bulb or tubular receptacle **110** 10.

and the receptacle is tubulated in a familiar manner for pumping. In the process as carried on commercially, a number of receptacles are prepared in this way and they are 5 then attached to the manifold 11 of an exhaust or vacuum pump 14.

The tubular bulbs or receptacles 10 are then in alternation exhausted of air and then flushed with clean, dry air. This step 10 of the process is continued until substantially all moisture has been removed from the inner surfaces of the receptacles. The air may be conveniently dried by passing it through several acid drier vessels 18 and 19, 15 and I have found that the alternate exhausting and flushing steps should be continued about four times. This is the first or rough pumping stage of the process and the receptacles in this stage are exhausted at each 20 pumping operation to a vacuum of approximately one-tenth of a millimeter.

A final flushing of dry air is given to the receptacles with air, which, in addition to being passed through the acid driers 18 and 25 19, is passed through a final drying vessel such as those just mentioned but containing anhydrous phosphorous, which removes the last traces of moisture in the air and thus makes it capable of taking up the last traces 30 of moisture in the detector receptacle. In exhausting the last charge of flushing air the vacuum is carried to approximately 1/100 of a millimeter.

The metallic elements of the device are 35 now connected in multiple at the external connection of the same (to preclude arcing between elements) and while enclosed in a maintained vacuum, said elements are subjected to a high frequency potential, (preferably 40,000 volts) one terminal of the potential being the elements enclosed in the vacuum tube, and the other terminal, ground, as shown in the drawing. We have thus a condenser effect between the metal elements, 40 exhausted tube and ground through ordinary atmospheric pressure. The elements are thus subjected to an electrostatic action of a high frequency high voltage.

This step of the process acts to disrupt 50 and to drive off the more readily vaporizable or volatilizable elements on the surfaces of the metal and other parts within the tube. The passage of the vapors or gases may be observed by the fluorescence resulting from 55 this treatment, which is continued (the process of exhaustion being carried on at the same time) until the fluorescence ceases and disappears. External heat is then applied to the tubes, in any convenient, well-known manner as by the coils 13, to drive off such 60 vapors as have condensed upon the inner surfaces of the tubes. A temperature of approximately 600° F. applied to the tubes will generally be sufficient. At this stage the exhaustion is continued to the limits of a mer-

cury condensation pump, that is to say, to the production of an almost perfect, commercially productive vacuum in the tubes.

The so-called hot element of the detector, namely, the filament, is now heated to incandescence by applying an alternating current to its terminals and a direct current of substantially 220 volts is applied to the cold or plate element of the detector, the positive terminal being connected to the plate element and the negative terminal being connected to the filament. The current applied to the filament is adjusted to produce incandescence of the filament slightly above normal,—that is to say, above that which it should have if used as the lighting element in an incandescent lamp,—and until fluorescence occurs between the filament and the plate element. The plate element becomes heated to a point somewhat above the normal low temperature which it attains, when the detector is in use, but not to a temperature to occlude all of the volatilizable constituents of the plate. This brings about the dislodgment, disruption and volatilization 70 75 80 85 90 95 100 105 110 115 120 125 130 of constituents on the surfaces of the parts within the tubes, which are less readily vaporizable or volatilizable than those already driven off, as heretofore described. The passage from the tubes of the gases or vapors is indicated by fluorescence. The treatment is continued, the gases or vapors being exhausted as before, for about fifteen (15) minutes, at the end of which period the tubes are again heated externally, to drive off such vapors or gaseous matters as may have condensed on the inner surfaces of the tubes. A temperature applied to the tubes of about 550° to 600° F. and continued for about ten (10) minutes will suffice.

In the last treatment, the filament is subjected to a temperature greater than it will be subjected to in the normal use of the detector and the cold element is subjected to a voltage many times above normal. This treatment being continued for the time mentioned, a great part of the volatilizable elements on the parts within the tubes will be disrupted and driven off, but there will be left on the metal parts within the tube, especially the plate, an amount or reservoir of what may be called latent volatilizable or vaporizable constituents, there being enough of such volatilizable constituents remaining, that the tube will retain its balance as a soft tube, without danger of breaking down when used with the normal voltages impressed in operating.

I have found that detectors where the receptacles or tubes have been exhausted in this manner, will always be of uniform softness; will all operate with a maximum of efficiency for the kind or style of detector employed; will have a maximum of efficient life; and will operate with almost entire

absence of all extraneous noises and tone vibrations.

I claim as my invention:—

1. The process of exhausting detector tubes which consists in exhausting and extracting all moisture from the tube; in then disrupting and driving off the more easily detachable volatilizable constituents on the elements of the tube by subjecting them simultaneously to the electrostatic action of a high frequency high voltage, afterwards applying external heat to drive off such constituents as have condensed on the inner surface of the tube; in then heating the filament above normal and subjecting the plate element to direct current at high voltage for a predetermined length of time, then again externally heating the tube to drive off condensation from its inner surface, and then sealing the tube.

2. The process of exhausting detector tubes, which consists in cleansing the metal elements of the detector before sealing them in the tube; in then exhausting the tubes and extracting all moisture therefrom; then disrupting and driving off the more easily detachable volatilizable constituents on the metal elements by subjecting them simultaneously to the electrostatic action of a high frequency high voltage, afterwards applying external heat to drive off such constituents as have condensed on the inner surfaces of the tubes; then heating the filament

above normal and at the same time subjecting the plate element to direct current at high voltage for a predetermined length of time; then again externally heating the tubes to drive off condensation from their inner surfaces; and then sealing the tubes.

3. The process of exhausting detector tubes, which consists in cleansing the metal elements to remove all extraneous matter before sealing them in the tubes; in then exhausting and extracting all moisture from the tubes by subjecting them alternately to exhaustion and flushing with dried air; in then disrupting and driving off the more easily detachable volatilizable constituents on the metal elements by subjecting said elements simultaneously to the electrostatic action at substantially 40,000 volts of high frequency, afterwards applying external heat to drive off such constituents as have condensed on the inner surfaces of the tubes; in then heating the filament by alternating current to incandescence above normal and subjecting the plate element to direct current at substantially 220 volts for a predetermined length of time, then externally heating the tubes to drive off condensation from their inner surfaces; and then sealing the tubes.

In testimony that I claim the foregoing as my invention, I affix my signature this 5th day of April, A. D. 1922.

ROBERT T. ST. JAMES.
